UNITED STATES PATENT OFFICE.

HENRY R. EDGECOME, OF ST. MARYS, PENNSYLVANIA, ASSIGNOR TO SPEER CARBON COMPANY, A CORPORATION OF PENNSYLVANIA.

BRUSH FOR DYNAMO-ELECTRIC MACHINES.

1,323,970.

Specification of Letters Patent.

Patented Dec. 2, 1919.

Application filed August 29, 1917. Serial No. 187,134.

To all whom it may concern:

Be it known that I, HENRY R. EDGE-
COMB, a citizen of the United States, and a
resident of St. Marys, in the county of Elk
5 and State of Pennsylvania, have invented a
new and useful Improvement in Brushes for
Dynamo-Electric Machines, of which the fol-
lowing is a specification.

My invention relates to current-collecting
10 brushes for electric generators, motors and
other dynamo-electric machines, and it has
for one of its objects to provide an improved
means for attaching a shunt or pigtail con-
ductor to a brush of the character indicated,
15 whereby the brush and the shunt conductor
may be easily and quickly assembled in a
permanent manner and with good electrical
contact between the several parts.

Another object of my invention is to pro-
20 vide a simple and rapid process of assem-
bling brushes of the above-indicated char-
acter.

The single figure of the accompanying
25 drawing is a side view, partially in elevation
and partially in section, showing a current-
collecting brush provided with a shunt con-
nection constructed in accordance with my
invention.

A large number of shunt attachments
30 have been devised for electric brushes, in-
volving the use of various forms of plugs
and screws for holding the shunt conductor
firmly in the brush. When screws have
35 been employed for this purpose, it has been
necessary to provide countersunk openings
in the brushes to receive the heads of the
screws, and it has also been necessary, in
assembling brushes and shunt conductors by
40 means of screws, to screw the parts together
with a screw driver or equivalent tool, which
makes the labor cost relatively high.

According to my present invention, I pro-
vide an attachment for shunt conductors in
which a screw-threaded member is employed,
45 but in which the pitch of the threads upon
the screw-threaded member is made suffi-
ciently long to permit the member to be
thrust directly into a suitable opening in
the brush, without the use of a screw-driver
50 or other similar tool. Several advantages
result from this arrangement. Not only is
the screw forced into place in a single short
movement, but the portions of the body of
the brush adjacent to the screw are macer-
55 ated slightly and form a firm interlock be-

tween the screw and the brush which is
not easily dislodged, even under severe
service conditions. Furthermore, the open-
ing which is provided in the brush to re-
ceive the screw need not be countersunk, 60
since the screw may be made without a
head, in the form of a simple threaded pin.
If the screw is so constructed, it is not nec-
essary to grind off the head of the screw, as
in many of the screw-attachments hereto- 65
fore designed.

As illustrated in the accompanying draw-
ing, the body portion of the brush 1 is pro-
vided with a longitudinal opening to re-
ceive a braided shunt conductor 2 and with 70
an intersecting transverse opening to receive
a screw-threaded pin or plug 3. The pin
3 is provided with one or more threads 4, of
long pitch, in order that there may be nu-
merous points of contact between the screw 75
and the body portion of the brush. The
brush may be made of any usual or desired
conducting material, such as graphite or a
mixture of carbon and metal.

In assembling the brush shown in the 80
drawing, suitable openings are drilled in the
body portion of the brush, as indicated, the
stranded conductor 2 is thrust into the ver-
tical opening, and the screw 3 is forced 85
firmly into the transverse opening. This
constitutes the entire assembling operation,
unless the screw employed is too long and
projects from its opening, in which case the
projecting portion should be clipped off in
90 order that the side of the brush may present
a smooth appearance. This, however, will
not ordinarily be the case, since the screws
are so proportioned, in practice, that the
outer end of the screw is forced below the
95 surface of the brush.

This brush construction lends itself well
to multiple assembling. Any desired num-
ber of brushes may be assembled with their
shunt conductors at one operation, by pro-
viding a suitable press having two coöperat-
ing platens, placing the brushes upon one
100 of the platens with their transverse open-
ings upward and with their shunt conductors
thrust into the longitudinal openings,
placing screws of the kind described above
105 in the transverse openings, and finally
bringing the other platen down upon the
screws to force them into place.

It is of course possible to make use of
ordinary multiple-threaded fillister-head 110

screws in making my improved shunt attachments, in which case the transverse opening in the body portion of the brush should be counterbored, to receive the head of the screw, or provision should be made for removing the head of the screw after the parts are assembled. It is also entirely practicable to assemble the brush with the axis of the screw coincident with the axis 10 of the shunt conductor at the point of attachment. Many other variations may be made from the exact structure which I have shown and described, and I therefor desire that no limitations be imposed upon my invention except such as are indicated in the appended claims.

I claim as my invention:

- 20 1. A current-collecting brush for dynamo-electric machines comprising a body portion of conducting material, a conductor therefor, and means for attaching the said conductor to the said body portion comprising a screw-threaded fastening member adapted to be thrust directly into interlocking contact with the said body portion.
- 25 2. A current-collecting brush for dynamo-electric machines comprising a body portion of conducting material provided with intersecting longitudinal and transverse openings, a conductor extending into one of the said openings, and a screw forced into interlocking contact with the walls of the other opening.

3. A current-collecting brush for dynamo-electric machines comprising a body portion of 35 conducting material provided with intersecting openings, a conductor extending into one of the said openings, and a screw forced into locking contact with the walls of the other opening.

4. The method of assembling current collecting brushes for dynamo-electric machines that comprises forming intersecting openings in a body portion of conducting material, placing the end of a conductor in 45 one of the said openings, and thrusting a screw-threaded fastening member into interlocking contact with the walls of the other opening and through the said conductor.

5. The method of assembling current collecting brushes for dynamo-electric machines that comprises placing a plurality of conducting body portions upon one of a pair of coöperating pressure members, the said body portions being provided with intersecting openings, placing a conductor in 55 one of the said openings in each of the said body portions, placing a screw in each of the remaining openings, and moving the said pressure members together and thereby 60 forcing the said screws into the said openings and through the said conductors.

In testimony whereof, I have hereunto subscribed my name this tenth day of August 1917.

HENRY R. EDGEcomb.
